UNITED STATES PATENT OFFICE

2,051,441

WASHING MACHINE

Charles Ellis, Victoria, British Columbia, Canada

Application September 16, 1935, Serial No. 40,853

1 Claim. (Cl. 141—9)

This invention appertains to new and useful improvements in washing machines.

The principal object of the present invention is to provide a washing machine wherein the articles washed are not subjected to any damaging impacts such as occur in washing machines having movable parts for agitating the articles being washed.

Another important object of the invention is to provide a washing machine employing air as the agitating force for the washing fluid.

Still another important object of the invention is to provide a washer employing air as an agitating medium for the washing fluid and wherein the washing fluid can be conveniently drained off after articles have been washed and the air kept under supply, to the end that the articles after having been washed can be dried by the air.

These and various other important objects and advantages of the invention will become apparent to the reader of the following specification:

In the drawings:

Figure 1 represents a top plan view of the apparatus.

Figure 2 represents a side elevational view of the apparatus.

Figure 3 represents a vertical sectional view taken substantially on line 3—3 of Figure 1.

Figure 4 is a horizontal sectional view taken substantially on line 4—4 of Figure 3.

Figure 5 is a bottom plan view of the air receiver.

Figure 6 is a vertical sectional view taken substantially on line 6—6 of Figure 1.

Referring to the drawings wherein like numerals designate like parts, it can be seen that numeral 5 represents a tank or tub having the bottom wall 6 and mounted on the legs 7. The bottom 6 is provided with a depending neck 8 in which the stopper 9 can be placed. This stopper is provided with a finger grip 10 at its top.

Numeral 11 represents an air receiver having the top wall a, the bottom wall b and the short inclined side walls c. Extending through the top and bottom walls a—b is the cylinder 12 which affords a clearance in the air receiver so that a person reaching downwardly through the tub can obtain access to the plug 9 so as to remove or place the same with respect to the drain neck 8. The top a of the air receiver is provided with openings 13 as are the side walls c, while the bottom wall b is provided with openings 14.

As shown in Figures 1 and 6, adjacent the tub 5 is the housing 15 mounted upon suitable legs 16 and in this is mounted the high speed motor 17. Numeral 18 represents the air inlet, while numeral 19 represents the air outlet pipe. The

high speed motor 17 drives the multi-blade fan 20. Numeral 21 is an ovate shaped casing between one end of which and the pipe 19 is the control valve 22. An elongated tube of suitable insulation is denoted by numeral 23 and is suspended in the casing 21 by suitable bolts 24. A heating coil 25 is wound on the tube 23 and the ends thereof are extended through insulating plugs 26 in the casing 21 to lead to a suitable wall plug or other electrical connection.

The remaining end of the heater casing 21 is connected as at 27 to the conduit 28 which extends to the lower portion of one side wall of the tub 5 to communicate with the air receiver 11.

It can now be seen that in operation, a sufficient volume of water and quantity of soap is placed in the tank and the dishes are placed upon the receiver 11. The motor 17 is now started and this supplies air through the pipe 19 and conduit 28 to the receiver 11 and the air at this point with considerable velocity escapes through the openings 13 upwardly, agitating the water and thus washing the articles upon the receiver 11.

Numeral 29 represents a cover for the tub 5 which is provided with downwardly struck openings 30 forming internal burrs 31 which will break soap bubbles forming upon the water content of the tub which would escape from the tub.

When the dishes or other items have been sufficiently washed, the plug 9 is drawn to permit the water and soap to drain off. The air supply is left on and when all of the water has escaped, air continues with force to contact the dishes until they are substantially dry. Thus the machine not only serves as a washer but also as a dryer.

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:

A dish cleaning and drying machine comprising a tub, a forced air supply conduit extending into the tub adjacent the bottom thereof, a shell mounted in the tub in close spaced relation to the bottom thereof, and with the interior of which the conduit communicates, said shell extending over substantially the entire area of the bottom of the tub, said shell being provided with inclined side walls, said inclined side walls and the top and bottom of the shell being provided with perforations, said inclined side walls terminating in close spaced relation with respect to the side walls of the tub.

CHARLES ELLIS. 60
